UNITED STATES PATENT OFFICE.

RUDOLPH J. WIG, OF WASHINGTON, DISTRICT OF COLUMBIA.

TREMIE.

1,280,345.

Specification of Letters Patent.

Patented Oct. 1, 1918.

Application filed October 12, 1917. Serial No. 196,216.

To all whom it may concern:

Be it known that I, RUDOLPH J. WIG, a citizen of the United States, residing at Washington, District of Columbia, have invented certain new and useful Improvements in Tremies; and I hereby declare that the following is a full, clear, and exact description thereof, reference being had to the accompanying drawings, which form part 10 of this specification.

This invention is a novel improvement in means for placing concrete in position under water, and has particular reference to the machines, commonly known as "tremies", 15 whereby the concrete mixture is conducted from above the surface of the water to the desired point beneath the same.

A "tremie" ordinarily consists of a pipe, usually from 8 to 14 inches in diameter and 20 either of uniform or slightly tapered bore, and from 10 to 50 feet in length, depending upon the depth of the water in which the concrete is to be placed. The lower end of such pipe is sometimes provided with a gate 25 or valve, or a plug is placed in the pipe, to prevent the concrete mixture segregating while passing through the pipe, and to cause it to force the water out of the pipe ahead of the concrete mixture when the first 30 charge of such mixture is placed in the tremie. After such tremie has been filled with concrete it is lowered into the water until its lower end rests on the bottom within the form wherein the concrete is to be 35 placed. The tremie is then slowly raised, an inch or so, until the concrete mixture starts to flow out of it and then concrete mixture is fed into the upper end of the tremie as the concrete mixture flows out of 40 the lower end thereof as the tremie is moved and slightly raised, this operation being continued until sufficient concrete mixture has been deposited in the form. Great care must be exercised during this operation not 45 to lift the tremie so high from the bottom as to disturb the balance of pressure which would cause the concrete mixture to flow out with such velocity that the entire charge in the tremie might escape; and the tremie 50 could not be then refilled without lifting it out of the water, replugging, refilling with concrete mixture, and then again submerging its lower end and carefully proceeding as stated.

55 My invention consists in providing means for positively controlling the escape or flow

of concrete mixture from the tremie, and provides a positive discharge, or feed device at the bottom of the tremie which device also acts as a gate to prevent the accidental loss or escape of a charge of concrete in the tremie, or while moving the tremie from place to place in the form, and which does not require the careful balancing of pressures of the mass of concrete inside the tremie and of the water at the discharge end thereof in order to insure the desired flow of the concrete mixture.

I will describe the invention with reference to the accompanying drawings which conventionally illustrate one practical embodiment thereof, and an understanding of such construction will enable others skilled in the art to adapt and use the invention. The features of the invention for which protection is desired are epitomized in the claims following such description.

In said drawings:

Figure 1 is a longitudinal vertical sectional elevation of a tremie embodying my invention.

Fig. 2 is an enlarged detail vertical section of the feed screw operating means.

Fig. 3 is an enlarged transverse section on the line 3—3, Fig. 2.

Fig. 4 is an enlarged transverse section on the line 4—4, Fig. 1.

In the example shown the tremie comprises a pipe 1, which may be of any desired length and internal diameter, and is preferably connected at its upper end to a hopper 2 of any desired form and size into which the concrete mixture can be fed to keep the pipe 1 filled therewith.

Extending transversely across the hopper 95 is a supporting bar 3 to which the upper end of a shaft 6 is rotatably connected; said shaft preferably depending through the bar and hopper and extending axially of and into the pipe 1. Any suitable means may be provided for rotating this shaft 6.

As indicated in Figs. 1 to 3 the shaft 6 has a gear 6^a on its upper end, above bar 3, which gear is keyed to the shaft; and said gear and shaft may be supported by ball 105 bearings 6^b upon the bar 3 so that the shaft may be turned with less friction.

The gear 6^a is preferably a worm gear and may mesh with a worm 5^a on a shaft 5 which may be journaled in brackets 4 on the bar 3. Shaft 5 may be driven in any suitable manner either manually or by power actuated

means as desired; and is shown as provided with a crank or handle 5^c on its outer end by which it can be manually turned.

Connected to the lower end of the shaft 6 is a discharge or packing screw 7, which may be of any suitable construction and have one or more flights. The screw flights should be sufficiently extended to substantially close the lower end of the pipe, when viewed from above (see Fig. 4); and said screw not only acts as a means to discharge material from the pipe, but also as a means to retain the material in the chamber or space in the pipe above the screw and below the hopper, unless the shaft is rotated.

If desired the lower end of the shaft 6 might be stepped in a transverse bar in the lower end of the pipe, but this is not essential as the screw could be made of a diameter to fit and to center itself within the end of the pipe. However, if desired, such a bar may be placed in the pipe as shown at 7^a in Fig. 1; and if the tremie and shaft 6 are very long additional bracing bars 7^b may be placed at intervals along the length of the shaft as indicated in Fig. 1.

If desired the part of the shaft in the space above the packing screw may be incased by a sleeve 8 which can be attached at its upper end to the bar 3 and at its lower end if desired to one of the transverse bars 7^b within the pipe. The sleeve 8 need not rotate and will prevent contact of the concrete mixture in the pipe with the shaft 6.

In using this device the tremie pipe 1 is first filled with a concrete mixture of the desired consistency, the concrete mixture being retained therein by the screw 7 in the lower end of the pipe, so that it cannot escape therefrom in mass. The tremie is then lowered into the water, in the usual manner, and when in proper position the concrete mixture can be discharged therefrom regularly and at will as desired by rotating the shaft 1, thereby operating the screw 7 and discharging the concrete mixture from the pipe as rapidly as desired; the flow of the concrete mixture being controlled and regulated by the speed of rotation of the screw.

By this novel means it is possible not only to feed the concrete mixture uniformly and at will, but also to pack the concrete, if desired, as it is discharged, as the action of the screw forcibly expelling the concrete mixture from the tremie can be used to pack the concrete beneath the tremie.

With this device the concrete mixture, when of proper consistency, cannot escape in mass, or in a rush from the tremie; but can be fed therefrom as desired, according to the speed of rotation of the screw.

The amount and weight of the superposed mass of concrete mixture in the tremie above the packing screw may vary but the concrete mixture can be discharged at will uni-

formly and regularly from the pipe as long as the screw is properly operated.

I have shown the packing screw operated by a shaft arranged inside of the tremie, this being a very simple construction, but I do not consider the invention limited to such an arrangement, and the form and construction of parts can be varied while retaining the essentials of the invention a distinguishing characteristic of which is the mechanical control of the concrete mixture in the tremie; and a regulable flow of concrete mixture therefrom, independently of the amount of concrete mixture in the tremie above the control device or screw and regardless of the length of the tremie.

What I claim is:

1. In a tremie, the combination of a pipe, a shaft therein, a screw in the lower part of the pipe connected with said shaft, a sleeve surrounding the shaft above the screw, and means for rotating said shaft.

2. In a tremie, the combination of a pipe, a shaft therein, a hopper at the upper end of the pipe, a screw in the lower part of the pipe connected with said shaft, a sleeve surrounding the shaft above the screw, and means for rotating said shaft.

3. In a tremie, the combination of a pipe, a hopper at the upper end thereof, a shaft disposed axially of said pipe, a packing screw in the lower part of the pipe connected with said shaft, for controlling the escape of concrete mixture from the pipe, a sleeve surrounding the shaft above the screw, and means for rotating said shaft.

4. Means for placing concrete under water, consisting of a conduit having a space for the reception of concrete mixture, and means below such space and adjacent the lower end of the conduit for controlling the escape of the mixture therefrom.

5. Means for placing concrete under water, consisting of a pipe having a space for the reception of concrete mixture and means adjacent the lower end of the pipe and below said space for supporting the concrete mixture therein and controlling the escape of such mixture therefrom.

6. Means for placing concrete under water consisting of a pipe having a space for the reception of concrete mixture and means adjacent the lower end of the pipe and below said space for expelling mixture therefrom while supporting superposed mixture.

7. Means for placing concrete under water, comprising a hopper, a tubular conductor having a space below the hopper for the reception of concrete mixture, means below said space for supporting the concrete mixture therein and controlling the flow of the mixture therefrom, and means for operating said controlling means.

8. A tremie for placing concrete under water, consisting of a pipe having a space

- for the reception of concrete mixture and means below such space for expelling the concrete mixture therefrom. 15
9. In a tremie for placing concrete under water, the combination of a pipe having a space for the reception of concrete mixture, and a screw below the space for controlling the flow of concrete mixture therefrom while supporting the superposed mixture therein. 20
10. 10. In a tremie for placing concrete under water, the combination of a pipe having a space for the reception of concrete mixture, a hopper at the upper end thereof, and a screw in the pipe below said space for controlling the escape of concrete mixture therefrom and means for operating said screw. 25

In testimony that I claim the foregoing as my own I affix my signature.

RUDOLPH J. WIG.
